UNITED STATES PATENT OFFICE.

HARRY N. ALTER, OF CHICAGO, ILLINOIS.

LUMINOUS PULL-CHAIN PENDANT.

Application filed January 7, 1922. Serial No. 527,594.

To all whom it may concern:

Be it known that I, HARRY N. ALTER, a citizen of the United States, and a resident of Chicago, Cook County, and State of Illinois, have invented certain new and useful Improvements in Luminous Pull-Chain Pendants, of which the following is declared to be a full, clear, and exact description.

This invention relates to pull chains for that type of electric sockets which are commonly known as "pull chain sockets," and its principal object is to provide a luminous pendant which may be directly attached to the pull chain without the intermediary of any separate connection between the pendant and chain. Luminous pendants for pull chains are commonly constructed of hollow glass bodies coated on their internal faces with a luminescent composition, whereby they are made visible in the dark, and some metallic collar or connecting medium is attached to the pendant, which collar in turn is attached to the chain. This makes a comparatively expensive construction, and as very thin metal is used for the collar, there is more or less danger of the collar being torn from the chain in use.

Another object is to provide a luminous pendant which may be readily attached to the common and well known forms of pull chain to take the place of the common ball or body with which said chains are usually equipped. With these objects in view, this invention consists in the several novel features hereinafter fully set forth and claimed.

The invention is clearly illustrated in the accompanying drawing, in which:—

Fig. 1 is a side elevation of a fragment of pull chain of common form, with a luminous pendant, embodying a simple form of the present invention, applied thereto; Fig. 2 is a central longitudinal section taken on line 2—2 of Fig. 1; Fig. 3 is a central vertical section taken on line 3—3 of Fig. 2 and Fig. 4 is a horizontal section taken on line 4—4 of Fig. 2.

Referring to said drawing, the reference character 5 designates a pull chain of common and well known form, such as is in almost universal use on electric light sockets, commonly known as "pull chain sockets." As is well understood, by those skilled in the art to which this invention pertains, these pull chains are made up of small hollow thin shelled balls or spherical objects 6, having diametrically opposite holes through

which extend short stems 7, usually formed of wire. Each stem 7 extends from the hole of one ball to the hole of an adjacent one and has heads 8 formed on its ends, which are contained in the balls.

The pendant 9 is made of a hollow open ended glass body, and the internal face thereof is coated with a luminous substance 10, as is well understood, whereby it is made visible in the dark. Any suitable shape may be given the pendant, and this is immaterial so far as this invention is concerned. The diameter of the hollow space is slightly greater than that of the balls 6, to permit the pull chain to pass freely therethrough. One end of the hollow body is contracted to form a restricted opening 11 of approximately the same diameter as the diameter of the balls. The lowermost ball 6^a is flattened to increase its diameter in one direction, whereby said lowermost ball may engage with the underside 12 of the contracted portion 13, to thereby prevent the pendant from being pulled off the chain when in use.

In replacing the common pull chain knob or grip with a pendant, embodying the present invention, the chain is cut off immediately above the ball or grip, and the end of the chain inserted through the restricted opening 11 of the pendant 9, and passed out through the other end thereof. The thin walled endmost ball 6^a is then flattened with a pair of pinchers, or by striking it a blow with a hammer or other tool, to thereby elongate it along a line at right angles to the length of the chain. The head 8 of the stem 7, which is contained in the elongated ball 6^a prevents the shell of the ball 6^a from being flattened down into a thin piece, and forms a solid core, as it were, about which the shell is pressed down. The result is that the upper edge portion which bears against the underside of the contracted upper end of the luminous pendant, takes a rounded shape, which is not liable to crack upon.

Moreover, the pull chain and luminous pendant body are thereby directly connected, and other or additional members for connecting them are dispensed with. The device is therefore less expensive to construct, and because the pendant 9 can be attached to the chain by any one without the aid of tools other than a pair of pliers or a hammer, or the like, for flattening out the end-

most ball, it is more saleable and finds a ready market.

More or less variation of the exact details of construction is possible without departing 5 from the spirit of this invention; I desire, therefore, not to limit myself to the exact form of the construction shown and described, but intend, in the following claims, to point out all of the invention disclosed 10 herein.

I claim as new and desire to secure by Letters Patent:

1. A pull chain, composed of hollow, thin shelled bodies, connected by headed stems, 15 and a hollow open ended luminous pendant having a contracted portion containing an opening of substantially the same diameter as that of the hollow bodies of the chain, whereby the latter may pass therethrough,

the endmost hollow body being elongated 20 transversely of the length of the chain, to form a rounded shoulder engaging with the underside of said contracted portion of the pendant.

2. A pull chain, composed of hollow, thin 25 shelled bodies, connected by headed stems, and a hollow open ended luminous glass pendant, having a contracted end portion containing an opening of substantially the same diameter as that of the hollow bodies 30 of the chain, whereby the latter may pass freely therethrough, the endmost hollow body being somewhat flattened down upon the head of its connecting stem to form a rounded elongated shoulder, which engages 35 with the underside of said contracted end portion of the pendant.

HARRY N. ALTER.
